HOLDER FOR A REVOLVER LOADER

Paul P. Kubik, 304 Llewellyn Road,
Ambler, Pa. 19002

Filed Jan. 17, 1974, Ser. No. 434,133

Term of patent 14 years

Int. Cl. D3—02

U.S. Cl. D22—14

Fig. 1

Fig. 2

Fig. 3

*Fig. 5**Fig. 4**Fig. 6*

FIG. 1 is a perspective view of a first embodiment showing my new design for a holder for a revolver loader adapted to receive two revolver loaders;

FIG. 2 is a top plan view thereof;

FIG. 3 is a front elevational view thereof;

FIG. 4 is a side elevational view of a second embodiment showing my new design as used for a holder for one such revolver loader;

FIG. 5 is a back elevational view of the embodiment of FIG. 4; and

FIG. 6 is a perspective view of the embodiment of FIG. 4.

I claim:

The ornamental design for a holder for a revolver loader, substantially as shown and described.
